DESIGN FOR AN ARTILLERY WHEEL

Paul W. Gaenssle and Talmon A. Davenport,
Detroit, Mich., assignors to Budd Wheel Com-
pany, Philadelphia, Pa., a corporation of Penn-
sylvania

Application November 17, 1933. Serial No. 49,768

Term of patent 14 years

To all whom it may concern:

Be it known that we, PAUL W. GAENSSLE and TALMON A. DAVENPORT, citizens respectively of Germany and of the United States, residing at Detroit, in the county of Wayne and State of Michigan, have invented a new, original, and ornamental Design for an Artillery Wheel, of which the following is a specification, reference being had to the accompanying drawing which forms a part hereof.

Figure 1 is a perspective view of a wheel embodying our new design.

Figure 2 is an enlarged fragmentary elevation.
Figure 3 is an axial profile, whereas

Figure 4 is a transverse spoke section.

We claim:

The ornamental design for an artillery wheel as shown.

Signed at Detroit, county of Wayne, State of Michigan, this 15 day of November, 1933.

PAUL W. GAENSSLE.
